TRANSFERRING AND REVOKING MEANS FOR
WEFT REPLENISHING LOOMS

Archibald J. Herard, Auburn, Mass., assignor to Crompton & Knowles Corporation, Worcester, Mass., a corporation of Massachusetts

Filed May 18, 1961, Ser. No. 110,967
26 Claims. (Cl. 139—231)

This invention relates to improvements in weft replenishing looms with particular emphasis to bobbin transferring and revoking mechanisms, and it is the general object of the invention to associate these mechanisms to each other in a manner so as to render them more sensitive to response with respect to each other than has been contemplated hereinbefore.

Looms of the type to which the present invention applies and which have gone into extensive use usually employ a reserve bobbin magazine operating with bobbin transferring means including a transferring hammer remote from the transfer revoking means but connected thereto by a series of levers, rods, springs, etc. so that transmission of force from one to the other of the mechanisms, or vice versa, results in the disadvantage of being slow and sluggish with a disappointing degree of response between the mechanisms which oftentimes leads to faulty weft replenishment, and also to nonrevocation when bobbin transfer revocation is needed due to a shuttle being misaligned with the magazine, as is sometimes the case. Moreover, the type of loom referred to above operates with the usual reciprocating lay having a bunter thereon to engage the usual transfer latch during a weft replenishing operation with an impact to accelerate the latch and hammer connected thereto from zero velocity instantly to the lay velocity with the resultant disadvantage of unfavorable reaction of the transferring mechanisms in the form of vibration to cause, in many instances, erratic and faulty bobbin transfer from the magazine into the shuttle.

It is therefore an important object of the invention to overcome the disadvantages discussed above by connecting the transferring and revoking mechanisms adjacent each other to insure rapid response of the mechanisms relative to one another, and by providing the transferring mechanism with means to effect acceleration of the transfer hammer from zero velocity to lay velocity in a measured time period of the loom cycle to cause smooth operation of the transferring mechanisms and to avoid vibration thereof.

It is another object of the invention to positively interconnect the mechanisms in a manner such that movement of either mechanisms will effect simultaneous movement of the other mechanism whether such movement occurs during a weft replenishing operation or during revocation thereof.

Another object of the invention is to provide actuating means and means depending from the hammer respectively to be normally in nonactuating and nonpick-up positions but movable incident to a weft replenishing operation respectively to an actuating and pick-up position to establish an operable connection between the means during setting of the magazine for movement from the actuating and pick-up position to effect a weft replenishing operation.

It is another object of the invention to provide connecting means common to the actuating and depending means and also to the revoking means to insure said simultaneous movement.

Another object of the invention is to provide the revoking mechanism with a shuttle feeler normally in non-shuttle feeling position and movable incident a weft replenishing operation to shuttle feeling position and, when doing so, causing the actuating and depending means

2

to move successively for operable connection with each other due to the common connection.

Still another object of the invention is to provide placing means to initiate placing of the shuttle feeler to shuttle feeling position, said placing means being operatively connected to the magazine and deriving its motion therefrom to effect setting of the transferring mechanism for a weft replenishing operation during movement of the shuttle feeler to shuttle feeling position.

10 And yet another object of the invention is to provide yielding means in the form of a toggle between a fixed support and the revoking mechanism tending to rotate the latter in one direction to maintain the shuttle feeler normally in nonshuttle feeling position and the actuating and depending means in their nonactuating and nonpick-up positions respectively, and yieldable to permit the placing means to initially rotate the shuttle feeler in the opposite direction after which the yielding means completes movement of the shuttle feeler in said opposite direction to shuttle feeling position and the actuating and depending means to engaging position incident to a weft replenishing operation.

20 A further object of the invention is to provide actuator means on a going-part of the loom, such as a laysword, 25 to engage the actuating means when the latter is operably connected to the depending means to effect a weft replenishing operation.

25 A still further object of the invention is to relate the shuttle feeler, the common means, and the actuating and depending means in such a manner that, during a weft replenishing operation, the shuttle feeler will be reset to nonshuttle feeling position due to the transferring operation without causing disengagement of the actuating and depending means, and that, during revocation, movement 35 of the shuttle feeler by a misplaced shuttle to nonshuttle feeling position will cause simultaneously movement of said common means and actuating and depending means to effect separation of the latter two means to prevent a weft replenishing operation.

40 In order that the invention may be clearly understood reference is made to the accompanying drawings which illustrate by way of example the embodiments of the invention and in which:

45 FIG. 1 is a side elevational view as seen from the center of the loom having the invention applied thereto, certain of the parts being in section and certain of the parts being broken away for clarity,

FIG. 2 is a plan view looking in the direction of arrow 2, FIG. 1,

50 FIG. 3 is a vertical section looking in the direction of arrows 3—3, FIG. 1,

FIGS. 4, 5 and 6 are diagrammatic operational views illustrating a bobbin transferring operation,

FIG. 7 is a diagrammatic partial view illustrating the 55 resetting of certain parts of the transferring mechanism after a weft replenishing operation, and

FIGS. 8 and 9 are diagrammatic operational views showing revocation of a transferring operation due to a misplaced shuttle.

60 Referring particularly to FIG. 1, a loomside 1, of which there are two, supports a pivot shaft 2 on which a pair of layswords are mounted for reciprocation, there being only one laysword shown as at 3. The layswords, as is usual, mount at their upper ends a lay L for flight 65 support of a shuttle S during loom operation. The loom-sides journal a cam shaft 4 which carries a set of conjugate cams generally indicated at 5 operatively connected to a pair of rolls 6 and 7 on a lever 8 pivoted as at 9 to a bracket 10 fixed to the loomside. Lever 8 at its lower 70 end 11 has pivoted thereto as at 12 one end of a connecting rod 13 which has its other end connected to a pivot 14 supported by a member 15 attached to laysword 3 in

any approved manner. The opposite end of the loom (not shown) is also provided with similar conjugate cams and connections to the lay to aid cams 5 to reciprocate the lay at a given velocity during loom operation.

The loomside 1 supports a fixed stand 16 to which is attached a reserve bobbin magazine generally indicated at M. The magazine is of usual construction and is provided with four stacks of bobbins designated at 17, 18, 19 and 20. Each stack is under control of the usual vertical slides 21, 22, 23 and 24 respectively which are selectively raised and lowered, as is well known, by the usual horizontal color slide fingers 25 and 26. The magazine M is provided with a transfer setting shaft 27 rockable in right and left-hand bearings 28 and 29 on the magazine. Shaft 27 fixedly mounts thereon a shelf 30 engageable by one or another of the dogs 31, 32, 33 and 34 respectively of slides 17-20 inclusive to effect rotation of shaft 27 and lever 35 fixed thereto to set the magazine for a weft replenishing operation upon indication of weft exhaustion in a shuttle by a weft feeler not shown herein but well understood in the art.

The magazine and the operation thereof is well known and it is deemed sufficient to state here that upon indication by a weft feeler of depletion of a bobbin in a shuttle, shaft 27 and lever 35 thereon will be rocked from the position in FIG. 1 to that of FIG. 5 to place one of the bobbins from either of the stacks, depending upon selectivity by slide fingers 25 and 26, to a transfer station generally designated by the character reference TS, see FIGS. 1 and 5. Rocking of shaft 27, as described above, will set the magazine and the transferring and revoking mechanisms, yet to be described, for a weft replenishing operation. Subsequently the bobbin at the transfer station will be transferred into a depleted shuttle by a bobbin transferring hammer 36 described hereinafter. The magazine forms no part of the present invention, except as set forth hereinafter, as neither does the cam driven lay, the drive mechanism therefor being set forth in copending application, Serial No. 110,945, filed on May 18, 1961 by Clarence R. Kronoff.

In carrying the present invention into effect, see FIGS. 1-3, the transferer hammer 36 has a depending rod means 37 pivoted at its upper end as at 38 to the hammer and its lower end free and suspended and yieldingly held in a relatively forward position with respect to the front of the loom. The lower end of rod 37 carries a lower bifurcated rod head 39 formed with a pair of spaced prongs 40 and 42 bridged by a stud 43 to form a closed slot 44. The upper end of rod 37 has secured thereto an upper rod head 41 on pivot 38, rod heads 39 and 41 being adjustably secured to rod 37.

A support 45 is fixed to the loomside in any approved manner and is provided with a pivot 46 on which a revoking mechanism generally indicated at 47 is pivoted. The revoking mechanism includes an operative connection in the form of a rotatable support or lever 48 movable about pivot 46 and carries a shuttle feeler 49 normally in forward nonshuttle feeling position as shown in FIG. 1. A sliding rod 51, see FIG. 2, has one end thereof pivoted to a shoulder bolt 52 on arm 48 and the other end thereof passing through a rotatable stud 53 on the fixed support 45. A compression spring 54 is interposed between shoulder bolt 52 and stud 53 to form toggle means which is located between the shuttle feeler support 48 and fixed support 45. A pair of stop screws 55 on rod 51 limits movement of the support 48 about pivot 46 in both counter and clockwise directions. As can be seen in FIG. 1, the toggle means exerts a force in a direction about pivot 46 to maintain the movable support and operative connections in nonoperative position, and as shown in FIG. 5, the toggle means acts in the opposite direction to hold the support and connections in operative position for weft replenishment.

Support 48 has fixed thereon and forwardly of pivot 46

a pin 56 on which a two-armed lever generally designated at 57 is rockable on and movable with support 48. Upper arm 58 of lever 57 is formed with a U-shaped part 59 to partially encircle rod 37, and lower arm 61 of lever 57 is operatively connected to a lever cam generally designated at 62 by means of a pin 63 on lever 62 and a slot 64 in lower arm 61. Resilient means in the form of a spring 65 has one end trained around and held by anchor 66 on fixed support 45 and the other end free against rod 37 to exert a force in a direction to maintain rod 37 seated in U-shaped part 59 and in normal nonpick-up position. Lever 57 may be considered as primary or common connecting means between the revoking mechanism 47 and rod 37 which may be termed secondary force transmitting means, and lever cam 62 may be referred to as actuating or primary force transmitting means.

Referring particularly to FIG. 1, lever cam 62 at one end thereof is pivoted as at 67 to loomside 1 and is provided with latching means including a reduced part 68 at the other end thereof to form a shoulder 69 for operable connection with pin 43. Lever 62 has adjustably mounted thereon a cam plate 71 having a rearwardly facing inclined surface 72 for engagement by actuator means including a force applying roll 73 on a bracket 74 fixed to laysword 3. Lever cam 62 is normally out of the path of travel of actuating means 73. Hammer 36, rod 37, levers 57 and 62 may be termed as bobbin transferring mechanisms.

With reference to FIGS. 2, 4 and 5, movable support 48 carries a second pin 76 slidable in a closed slot 77 formed at the lower end of a rod 78, the upper end of which is pivotally connected to lever 35 on setting shaft 27. Rod 78 may be considered as placing means for revoker 47, and shaft 27 may be termed as means to set the magazine for a weft replenishing operation. It is to be noted that in effect movable support 48 and revoker 47 are one and the same, being utilized to carry shuttle feeler 49.

During loom operation, the shuttle S will be picked back and forth across the loom in any approved manner 40 and will in the weaving process lay weft filling, not shown, from a bobbin B in shuttle S, see FIG. 1. Upon depletion of the weft on bobbin B the magazine will be given an indication by a weft feeler, also not shown, whereupon either of the color slides 25 and 26 will raise one or the other of the slides 21-24 in the usual manner to place either of the dogs 31-34 over shelf 30 as the case may be. Subsequently, color slides 25 and 26 will have a down motion to lower the selected vertical slide to cause its corresponding dog to engage shelf 30 and rock the latter and lever 35 from the position shown in FIG. 1 to that shown in FIG. 5. Rocking of shaft 27, as is usual, sets the magazine for a weft replenishing operation, that is, it effects movement of one of the bobbins 17-20 to the transfer station TS as illustrated in FIG. 5.

When shaft 27 is rocked as discussed above, rod 78 will be lifted upwardly and the lower end thereof will move pin 76 also upwardly and about pivot 46 to initiate raising of the shuttle feeler from nonshuttle feeling position in FIG. 1 to that of FIG. 4. During the initial movement of rod 78, shuttle feeler 49 and bolt 52 will be partially raised about pivot 46 to the extent to permit spring 54 to exert a force in a counterclockwise direction to complete lifting of the shuttle feeler from the position shown in FIG. 4 to shuttle feeling position shown in FIG. 5. Rotation of the shuttle feeler about pivot 46 causes pin 56 and lever 57 to be lifted around pivot 46. During initial rotation of the shuttle feeler counterclockwise, lever 57 will raise lever 62 from nonactuating position of FIG. 1 to the position shown in FIG. 4 and will 60 also move pin 43 by reason of U-shaped part 59 adjacent to reduced part 68. Continued motion of the shuttle feeler will be effected by spring 54 to cause part 68 to be raised to actuating position and pin 43 moved below shoulder 69 to pick-up position with part 68 between prongs 40 and 42 in slot 44 to establish an operable con-

nection between lever 62 and rod 37. The loom is now set for a weft replenishing operation, and it is to be noted that the force exerted by spring 54 is greater than that exerted by spring 65 and that the latter cannot unseat pin 43 from shoulder 69. At this time the lay is in its back position as shown in FIG. 5, and as the lay moves forwardly by reason of cams 5 roll 73 will engage surface 72 on lever 62 to accelerate the latter from zero velocity to lay velocity in a measured time period of the loom cycle to cause rod 37 and head 75 on hammer 36 to move downwardly from pick-up and actuating positions to transfer a bobbin from the transfer station into the shuttle S as can be seen in FIG. 6. When the operative connection 57 is raised, actuating means 62 and depending means 37 will move successively to actuating and pick-up positions, i.e., means 62 will be in actuating position before means 37 is in pick-up position.

During the bobbin transferring operation, lever 62 and pivot 56 will be moved downwardly and clockwise, thereby lowering and rotating shuttle feeler 49 to its non-shuttle feeling position.

When the transferring operation is completed as shown in FIG. 6, the lay will recede and a spring 30 on hammer pivot 31 will act to return hammer 36 and consequently rod 37 to the position shown in FIG. 1. During return of the transferring hammer, lever 62 will be lifted from the dotted line position to the full line position in FIG. 7 and rod 37 will slide along U-shaped part 59 during which spring 65 will exert a force to unseat pin 43 from shoulder 69 to effect movement of rod head 39 from the full line position to the dotted line position. During unseating of pin 43, the force of spring 54 will be exerted clockwise about pivot 46 and will not oppose the unseating force of spring 65. Upon completion of unseating pin 43 from part 68, the magazine and associated parts will be in readiness for further transferring operations. It will be noted from the various figures that the revoking and transferring mechanisms are interconnected and adjacent each other so that the force transmitted from roll 73 to lever 62 is positively and simultaneously transmitted therefrom to lever 57, rod 37 and hammer 36. This force is also transmitted to pin 56 simultaneously so that during weft replenishing operation the shuttle feeler will move also simultaneously with levers 57 and 62 and rod 37 but will not cause disengagement of pin 43 from shoulder 69.

In the event that a shuttle is not properly aligned with the transfer station incident a weft replenishing operation, the shuttle feeler will act to revoke the transfer. FIG. 8 represents a condition of a misplaced or a misaligned shuttle with the latter engaging the shuttle feeler as the lay is advancing. Roll 73 has not yet contacted surface 72, and as the lay continues to advance, shuttle S will move the shuttle feeler and pin 56 positively forwardly and rotationally about pivot 46 to effect quick response of the lever 57 which will move downwardly to lower lever cam 62 without roll 73 depressing surface 72. After the shuttle has moved the shuttle feeler a short distance, spring 54 will be in a position to exert a clockwise force about pivot 46 and will act to snap the shuttle feeler about its pivot 46 to nonshuttle feeling position as in FIG. 9. It will be noted that during setting of the transferring and revoking mechanisms for a weft replenishing operation as shown in FIGS. 5 and 8 pin 76 will be in the upper part of slot 77 when the shuttle feeler has reached shuttle feeling position. Consequently, the toggle can act rather rapidly to lower the pin and shuttle feeler after its positive initial movement by the shuttle to effect rapid lowering of surface 72 so that roll 73 will have no effect on surface 72 and cannot cause a faulty weft replenishing operation when a shuttle is misplaced.

From the foregoing it will be seen that simple means have been provided to effect a smooth weft replenishing operation by virtue of the fact that roll 73 will accelerate lever 62 from zero velocity to the lay velocity in a

measured time of the loom cycle and thus avoid undesired vibration of the transferring mechanism. Also it will be seen that the revoking and transferring mechanism are interconnected by common means and adjacent each other in a manner such that a graduate movement of one of the mechanisms will effect positive and graduate movement of the other so that response to revocation will be quite sensitive and rapid. Further, it will be seen that resetting of the revoker mechanism during a weft replenishing operation is accomplished by the operation of the transferring mechanism without disturbing the setting thereof. Also, simple yielding means has been provided to maintain the revoking and transferring mechanisms respectively in either nonshuttle feeling position and non-transferring position, or respectively in shuttle feeling position and shuttle transferring position respectively as the case may be, the yielding means being of the nature to permit movement of the mechanisms from one to another of said positions and vice versa.

20 I claim:

1. In a weft replenishing loom operable to replenish a depleted bobbin in a shuttle and having a reserve bobbin magazine provided with a bobbin transferring hammer and a transfer setting shaft rockable to set the magazine for a weft replenishing operation upon weft depletion of a bobbin, means depending from said hammer normally in a nonpick-up position but movable during setting of the magazine to a pick-up position for movement therefrom to cause movement of said hammer to effect a weft replenishing operation, actuating means for cooperation with said depending means normally in nonactuating position and movable to actuating position for operable connection with said depending means incident to a weft replenishing operation, operative connections between said depending means and said actuating means to move both means respectively to pick-up and actuating positions, and placing means between said setting shaft and said operative connections to effect movement of the latter to establish said operable connection during setting of the magazine for a weft replenishing operation.

2. The loom set forth in claim 1 wherein said depending means includes a rod having one end thereof adjustably secured to an upper rod head pivotally mounted on said hammer and having the other end thereof adjustably secured to a lower rod head having a stud for engagement by said actuating means to depress said hammer during weft replenishing operation.

3. The loom set forth in claim 2 wherein the lower rod head is bifurcated to form a pair of depending prongs through which said stud extends to form a closed slot for entrance of said actuating means therein.

4. The loom set forth in claim 1 wherein said actuating means includes a lever pivoted at one end to a stationary part of the loom and provided with a reduced part 55 of the other end to form a shoulder for operable connection with said depending means and also provided with a pin operatively connected to said operative connections.

5. The loom set forth in claim 1 wherein said operative connections include a pivoted vertical lever, the lower end 60 thereof being provided with a slot for connection with said actuating means and the upper end thereof being provided with a U-shaped part to freely surround the depending means, and a rotatable support to which said vertical lever is pivoted between its ends, said rotatable support being pivoted at one end thereof to a fixed support and having a pin operatively connected to said placing means.

6. The loom set forth in claim 5 wherein said operative connections also include resilient means interposed between said rotatable support and said fixed support to form a toggle connection therebetween.

7. The loom set forth in claim 5 wherein said operative connections also includes a spring means having one end thereof pivoted on said fixed support and having a free 75 end for engagement with said depending means, said

spring means exerting a force in a direction to maintain said depending means seated in said U-shaped part.

8. The loom set forth in claim 1 wherein said placing means includes a vertical rod having one end thereof pivotally connected to said setting shaft and the other end thereof provided with a closed slot for pivotal and sliding connection to said operative connections.

9. In a weft replenishing loom operating to replenish a depleted bobbin in a shuttle and having a reserve bobbin magazine provided with a bobbin transferring hammer and a transfer setting shaft operating to set the magazine for a weft replenishing operation upon weft depletion of a bobbin, depending means pivoted to said hammer normally in a forward nonpick-up position but movable rearwardly during setting of the magazine to a pick-up position for movement therefrom to effect movement of said hammer to replenish a shuttle, actuating means for cooperation with said depending means normally down in non-actuating position and movable upwardly to actuating position for operable connection with said depending means incident to a weft replenishing operation, operative connections between said depending means and said actuating means to simultaneously move both means respectively to pick-up and actuating positions to establish said operable connection, said operative connections acting to move said actuating means to said actuating position before said depending means reaches said pick-up position, placing means between said setting shaft and said operative connections to effect movement of the latter during setting of the magazine for a weft replenishing operation, and actuator means to engage said actuating means when the latter and said depending means are operably connected to move said actuating and depending means to effect a weft replenishing operation.

10. The loom set forth in claim 9 wherein said actuating means is a lever pivoted at one end and includes an adjustably fixed plate on said lever having an inclined surface for engagement by said actuator means when actuating means is in said actuating position.

11. The loom set forth in claim 10 wherein said inclined surface faces the rear of the loom and is normally out of the path of travel of said actuator means and movable into said path for engagement by said actuator means upon setting of the magazine.

12. The loom set forth in claim 9 wherein said actuator means is a roll on a going part of the loom during operation thereof.

13. The loom set forth in claim 12 wherein said going part is reciprocating laysword adjacent said actuating means.

14. In a weft replenishing bobbin changing loom provided with a pair of layswords reciprocating at a given velocity and a reserve bobbin magazine operating with a bobbin transferring hammer and a transfer setting shaft rockable to set the magazine for a weft replenishing operation upon depletion of a bobbin, actuator means on one of said layswords and moving therewith at said given velocity, hammer actuating means normally out of the path of said actuator means and movable into the path thereof during setting of the magazine for engagement with said actuator means, depending means pivoted to said hammer having a free end normally away from said actuating means but operatively connectable thereto upon movement of said actuating means into said path, operative connections between said actuating and depending means to move said free end into connection with said actuating means, placing means between said setting shaft and said operative connections to move the latter to place said actuating means in said path, and cam means on said actuating means provided with a surface for engagement by said actuator means when the actuating means is in said path, said surface being of a configuration to effect acceleration of said actuating means from zero velocity to said given velocity in a measured time period of the loom cycle to effect a weft replenishing operation.

15. In a weft replenishing loom operating to replenish a bobbin-carrying shuttle and having a reserve bobbin magazine operating with a bobbin transferring hammer and a transfer setting shaft rockable to set the magazine for a weft replenishing operation upon depletion of weft in said shuttle, depending means pivoted at one end to said hammer and having the other end normally in a nonpick-up position but movable to a pick-up position for movement therefrom to effect movement of said hammer to replenish a depleted shuttle, pivoted actuating means for said depending means normally in nonactuating position and movable to actuating position for operable connection with said depending means when the latter moves to said pick-up position incident to a weft replenishing operation, operative connections between said actuating and depending means normally in nonoperative position but movable to operative position incident to a weft replenishing operation, a movable support for said operative connections movable therewith and mounting a pivot therefor, a fixed support for said movable support, a pivot for said movable support on said fixed support, placing means between said setting shaft and said movable support to initiate movement of the latter during a magazine setting operation, resilient means having one end mounted on said fixed support and the other end exerting a force on said depending means to maintain the latter normally in said nonpick-up position, and spring toggle means between said movable support and said fixed support capable of exerting a force in a direction to maintain said movable support and operative connections in said nonoperative position and capable of exerting a force in a direction to move said movable support and said operative connections to said operative position subsequent to initial movement by said placing means to establish said operable connection.

16. The loom set forth in claim 15 wherein said spring toggle means exerts a force greater than said resilient means to overcome resistance thereof when said operative connections are moved to said operative position.

17. The loom set forth in claim 15 wherein said toggle means includes a rod pivoted at one end to said movable support and having its other end freely slidably in a rotatable stud pivoted on said fixed support, and a compression spring interposed between said one end and said rotatable stud, said spring tending to rotate said movable support in one direction when the latter is in nonoperative position and acting to rotate said movable support in a direction opposite said one direction subsequent said initial movement.

18. In a weft replenishing bobbin changing loom operating with a pair of reciprocating layswords and having a reserve bobbin magazine operating with a bobbin transferring hammer and a transfer setting shaft rockable to set the magazine for a weft replenishing operation upon weft depletion of a bobbin, rod means pivotally depending from said hammer and having its lower end normally free in a forward nonpick-up position and movable to a rear pick-up position incident to a weft replenishing operation, pivoted cam means normally down in nonactuating position but movable upwardly to actuating position incident to said replenishing operation, a pair of interconnected lever means between said rod and cam means operative incident to said replenishing operation to move said cam means upwardly to its actuating position in advance of said rod means while moving the latter rearwardly to its pick-up position for connection with said cam means, placing rod means connected at its upper end to said setting shaft and at its lower end to one of said pair of levers to effect movement of said levers by said setting shaft to place said depending rod and cam means respectively in said pick-up and actuating positions during setting of the magazine, and cam depressing means on one of said layswords to depress said cam means when the latter is in actuating position to cause said depending

rod means to move the transfer hammer downwardly to effect a weft replenishing operation.

19. The loom set forth in claim 18 wherein one lever of said pair of interconnected levers has an upper arm connected to said depending rod means and a lower arm connected to said cam means and is pivotally supported between said arms to the other lever of said pair of interconnected levers, said other lever being pivotal at a point rearwardly of the point at which said one lever is pivoted, the relationship of the two levers and their pivots being such that when said other lever is moved by said placing rod means to effect moving of said cam means to said actuating position, the said one lever will also move and said upper arm thereof will have a vertical and rearward motion to place the lower end of said depending rod means in pick-up position with respect to said cam means after the latter has reached said actuating position.

20. In a weft replenishing loom operating to replenish a depleted bobbin and having a reserve bobbin magazine provided with a bobbin transferring hammer and a transfer setting shaft operating to set the magazine for a weft replenishing operation upon weft depletion of a bobbin, primary force transmitting means normally in non-force transmitting position and movable to force transmitting position during setting of the magazine, secondary force transmitting means between said hammer and said primary force transmitting means and normally disconnected therefrom to prevent a force transmitting relationship, primary operative connections common to said primary and secondary force transmitting means movable to establish said force transmitting relationship therebetween incident to a weft replenishing operation, secondary operative connections common to and between said setting shaft and said primary operative connections to move the latter to cause said force transmitting relationship during setting of the magazine by the setting shaft, and force applying means to engage said primary means to apply a force thereto to move the primary and secondary means to transmit a force to said hammer subsequent to establishment of said force transmitting relationship to effect a weft replenishing operation.

21. In a weft replenishing bobbin changing loom having a bobbin reserve magazine with a transfer setting shaft rockable in one direction to set the magazine for a weft replenishing operation upon depletion of an active bobbin and operating with a bobbin transerrer provided with a pivot and a bobbin engaging head, force transmitting means having one end thereof pivoted to said transerrer between said pivot and said head and having the other end normally in nonforce transmitting position but movable to force transmitting position incident to a weft replenishing operation, other force transmitting means including latching means normally located away from said other end but movable for latching engagement therewith during movement of said force transmitting means to said force transmitting position, operative connections between said force transmitting and said latching means operable to move both latter means to latching engagement, an operative connection between the setting shaft and said operative connections to move the latter when said setting shaft is rocked in said one direction to effect movement of said force transmitting and latching means to establish said latching engagement, force applying means to engage said other force transmitting means when said latching means and said force transmitting means are in said latching engagement to transmit a force through both latter means to said transerrer to effect movement thereof to cause said weft replenishing operation, and yielding means acting on said force transmitting means to yieldingly maintain said other end in said nonforce transmitting position and yielding to permit said force transmitting means to move to said force transmitting position incident a weft replenishing operation, said yielding means also acting to effect unlatching of the force trans-

mitting means with respect to said latching means subsequent a weft replenishing operation.

22. In a weft replenishing loom operable to replenish depleted shuttles and having a reciprocating lay mounted on layswords and also having a reserve bobbin magazine provided with a bobbin transfer station and a bobbin transferring hammer and a magazine transfer setting shaft rockable to effect movement of a reserve bobbin to said station to set the magazine for a weft replenishing operation upon depletion of a shuttle, vertically movable means pivoted on and depending from said hammer and normally in an inactive position and swingable to an active hammer moving position incident to a weft replenishing operation, actuating cam means between the lay and the depending means normally in nonactuating position but movable to actuating position incident to said weft replenishing operation for operable connection with said vertically movable means, means mounted on one of said layswords for engagement with said actuating means when the latter is in actuating position to cause movement of said vertically movable means to effect a weft replenishing operation, operative connections between said vertically movable and said actuating means to move both means respectively to hammer moving and actuator positions, shuttle feeler means pivotally connected to said operative connections normally in nonshuttle feeling position and movable to shuttle feeling position incident to a weft replenishing operation, placing means between said shuttle feeler means and said setting shaft to effect simultaneous movement of the shuttle feeler to shuttle feeling position and successive movement of said actuator and vertically movable means respectively to said actuating and hammer moving positions when said setting shaft rocks to set the magazine for a weft replenishing operation, and interconnecting means between the shuttle feeler means and said placing means to permit resetting of the shuttle feeler means without disengaging said operable connection during a weft replenishing operation.

23. The loom set forth in claim 22 wherein said interconnecting means is a pin and slot connection, said pin being on said shuttle feeler means and said slot being on said placing means.

24. In a weft replenishing loom having a magazine employing a transferring hammer to transfer bobbins from the magazine into a shuttle upon depletion of a bobbin in a shuttle, setting shaft means rockable to set the magazine for a bobbin transferring operation when said depletion occurs, depending means pivoted at one end to said hammer and having the other end normally in a nonpick-up position but movable to a pick-up position during setting of the magazine, pivoted cam means normally disengaged from said depending means and movable to said pick-up position for engagement with said depending means, a shuttle feeler pivoted to a fixed support and provided with a pin for movement therewith, a lever mounted on said pin having one end connected to said depending means and the other end connected to said cam means, a second pin on said shuttle feeler movable therewith, placing means between said second pin and said setting shaft operating incident to a weft replenishing operation to move said shuttle feeler from a nonshuttle feeling position to a shuttle feeling position, and yielding means between said shuttle feeler and fixed support acting to normally hold the shuttle feeler in said nonshuttle feeling position and yielding to permit movement of the shuttle feeler to shuttle feeling position and thereafter maintaining the feeler in the latter position until moved by the transferring mechanism during a weft replenishing operation or engaged by a misplaced shuttle in which event the feeler will be moved to nonshuttle feeling position to effect revocation of a weft replenishing operation by causing disengagement of said depending means from said cam means.

25. In a weft replenishing loom provided with a reserve bobbin magazine operating to replenish a shuttle

upon depletion of a bobbin therein, said magazine being provided with a bobbin transfer station normally aligned with the bobbin in the shuttle during loom operation, a bobbin hammer to transfer a bobbin from said station to said shuttle during a weft replenishing operation, depending means pivoted to said hammer and having its lower end normally in a nonengageable position but movable to an engageable position incident a weft replenishing operation, cam means also normally in a nonengageable position but movable to said engageable position to engage said depending means when the latter moves to said engageable position, a shuttle feeler pivoted to a fixed support and movable from nonshuttle feeling position to shuttle feeling position when said depending and cam means move to said engageable position, an operative connection common to the shuttle feeler and said depending and cam means, means operating from the magazine to move said shuttle feeler to said shuttle feeling position while at the same time effecting simultaneous movement of said depending and cam means to said engageable position, and means to engage said cam means when in said engageable position to move the cam means to effect a weft replenishing operation and also to effect movement of the shuttle feeler to nonshuttle feeling position during said weft replenishing operation.

20

25

26. For a bobbin transferring loom, bobbin transferring mechanism including a bobbin transferring hammer having a hammer moving rod pivoted thereon, a rod moving lever cam separate from said rod but engageable therewith, common lever means adjacent and connected to and between said rod and said lever cam movable to cause engagement therebetween incident to a bobbin transferring operation, revoking mechanism including a shuttle feeler pivoted on said common lever means and also on a fixed support, and bobbin transfer setting means common to said shuttle feeler and said common lever including a rod connected to the shuttle feeler and movable incident a bobbin transferring operation to set the revoking mechanism to revoking position and the transferring mechanism to bobbin transferring position.
